PIERCING TOOL

Eldred O. Morton, Mansfield, Ohio, assignor to Westinghouse Electric & Manufacturing Company, East Pittsburgh, Pa., a corporation of Pennsylvania

Application April 1, 1944, Serial No. 529,229

4 Claims. (Cl. 164—119)

My invention relates to the manufacture of Pitot tubes for indicating the speed of the medium surrounding the Pitot tube with reference to the Pitot tube and, more particularly, my invention relates to a tool for use in the manufacture of certain elements of Pitot tubes.

Pitot tubes used for indicating the speed of aircrafts are often subjected to extremely low temperature at high altitudes and certain seasons. Such tubes are thus very likely to become clogged by ice and the intended function is thus not obtained. To eliminate the formation of ice, such tubes are provided with heaters, more particularly electric heaters, and the construction is such that the moisture they may collect as ice or slugs of liquid is, because of the heaters and suitable drain openings, discharged from the tube. To control the transmission pressure from the front of the tube and to heat the tube and fluid, the tube is provided in its interior with heat conducting plugs. These plugs housing the heaters, are brazed or soldered into position, and are provided with suitable channels to permit the dynamic and static pressure to be transmitted to the back of the tube and from there to the indicating instrument.

An object of my invention is to provide a special tool for providing the heat conducting plugs of a Pitot tube with the required channels for transmitting the dynamic pressure to the desired point.

A broad object of my invention is the provision of tube piercing tools for piercing tubes from the inside.

A more specific object of my invention is the provision of a suitably shaped tool that may be inserted in the open end of a metal tube, and by means of one simple manipulation, pierces the tube by the application of a piercing point or tooth to the inner surface of the tube and forcing the tooth through the tube material to project to the outer surface of the tube.

The principal object of my invention is to provide an improved method of manufacture of Pitot tubes that will require less labor time and will obtain a lower cost of manufacture.

The objects herein recited are merely illustrative and many other objects will become apparent from a study of the following specification and the accompanying drawings in which:

Figure 1 shows a longitudinal section of a Pitot tube illustrating the disposition of the heat conducting plugs in the tube;

Fig. 2 shows a side view of my special tool inserted into a heat conducting plug of a Pitot

tube, the plug being shown in longitudinal section and the tool being shown in its first operating position;

Fig. 3 is a view similar to Fig. 2 with the tool shown in its second operating position;

Fig. 4 is a transverse sectional view on line IV—IV of Fig. 2;

Fig. 5 shows how an alternative type of tool may be used for effecting the piercing operation;

Figs. 6 and 7 show further modifications of a tool for piercing a tube from the inside.

In one form of Pitot tube used for indicating the air speed of an aircraft, the tube has a cylindrical housing 1 provided with a nose 2 and an opening 3 at the front. The Pitot tube is mounted on the aircraft to point in the general direction the aircraft is moving so that the dynamic pressure may enter at opening 3. At the 10 inside the tube is provided with a front heat conducting plug 4 and a rear heat conducting plug 5. Plug 4 is brazed or soldered into the front of the tube just back of the drain openings 6 and houses the electric heater 7.

The plug 4 is provided with an upper channel for receiving the tube 8 having the side openings 9 for receiving the dynamic pressure of the fluid and for transmitting it to the lower well, or channel, 10 in plug 5. From channel 10 the pressure is transmitted through the vertical channel 11 in plug 5 to the tube 12 suitably connected to an indicating instrument (not shown). The tube 8 is, of course, hermetically sealed to the plug 4 and also hermetically sealed to the plug 5 at its entrance into the channel 10. Plug 5 also houses a heater in its upper well 26.

According to the prior art to provide the plug 5 with the vertical channel 11 so that the dynamic pressure may be transmitted to the tube 12, it was necessary to drill a hole from outside of the plug into the lower end of well 10 and then through the wall 13 at its right-hand end. This hole had to be tapped at 15 and a threaded plug 16 was then inserted and securely brazed into position so as to be leakproof. After the plug 5 was assembled in the tube 1 and the plug 5 securely brazed into place, a drain hole 17 was drilled through the tube 1 and through the closure plug 16 to provide a small opening so that the liquid that might collect in channel 10 was expelled through this drain hole 17.

From Fig. 4, it will be apparent that the separating wall 13 is relatively thin at 18. I, there-

fore, devised the special tool shown in Fig. 2 for piercing the plug at 18 from the inside.

This special tool may be made out of straight strap material 20 having a handle 21 and cut as at 22 and 23 to form the relatively thin region 24. From 24 towards the right, the width of the tool again increases up to about the region 25. At region 25 I not only increase the width of the tool but also increase the thickness as well so that the end at the right is substantially skull-shaped, considering the shape of a skull of a squirrel, minus the lower jaw. The skull-shaped portion, as seen from the right in Fig. 4, is so shaped and dimensioned as to substantially fill and conform at the upper region of the tool to the inner contour of the well 26 in the plug 5. The tool is cut away as shown at 27 and provided with a single relatively narrow tooth 28. The right-hand end of the tool may also be described as being shaped like the head end of a hooded cobra.

In operation, the tool is inserted in the upper well 26 from the left until it holds a position as shown in Fig. 2, then by merely moving the tool to the position shown in Fig. 3 in the plane including the axes of the channel 1 or well 10 and the well 26, the skull-shaped end is caused to nod forward. The dome of the skull acts as a fulcrum and the tooth pierces the tube at 18 so that an opening is formed between the well 10 and the well 26 at the right-hand end of the 30 wells.

In Fig. 5, I show a plug 5' similar to plug 5 shown in Figs 1, 2 and 3 but in this case I insert a tool from the left into the channel 10', the tool being a reamer or drill and by holding it at an angle, the separating wall 13' is broken at 18'.

In Fig. 6 I show a modification of my device for piercing a tube from the inside. In this showing I provide a base 30 upon which I mount the plug or block holding or positioning jig 31 having the groove 32. As is well known the plug 5 for its upper half region almost fills the housing 1 but it is provided with longitudinal grooves at each side of the lower portion having the channel 10. The lower portion is thus narrow. The groove 32 is designed to receive this lower narrow portion to thus correctly vertically position the plug 5 on the jig. The jig also has the stop 33 to axially correctly position the plug 5 on the base with reference to the tool 34. This tool 34 is shaped as shown and is pivoted on arbor 35. A spring 36 biases the tool 34 for counterclockwise rotation.

A tool operating lever 37 is pivoted on arbor 38 to which the cam 39 is keyed. The parts are shown in the operated position. By moving the lever 37 counterclockwise through a relatively small angle the cam 39 will move sufficiently so that the spring 36 will operate the tool 34 counterclockwise an amount sufficient to position the tool axis slightly elevated at the right. When the tool 34 is in this elevated position a plug is positioned on the jig. By merely depressing the lever 37 the tool is moved clockwise and the piercing operation is thus accomplished.

In Fig. 7 I show the piercing tool 40 positioned in the cylindrical guide element 41 having the cam portion 42 coacting with the cam surface 43 on the tool end.

The tool 40 is provided with a slot 44. A pin 45 rigidly mounted in element 41 guides the tool in its axial movement. I position a biasing spring 46 between the washers 47 and 48. Washer 47 is slidable on the tool whereas washer 48 rests against the backing pin 49. By holding the plug

5 in the desired relation to the tool and the element and by moving the tool, by the application of a force on the tool at the left, axially with reference to the element 41, the piercing operation is effected.

It will be noted that with the provision of my simple one-piece piercing tool, I eliminate all drilling, tapping and brazing operations that are required in connection with the closure plug 16 and I, therefore, provide a tool which effects a considerable saving in labor and in materials and thus effects a very important reduction in the cost of Pitot tubes.

While I have shown but a few constructions 15 for my piercing tools and suggested alternate methods of piercing a tube from the inside, I do not wish to be limited to the particular construction shown but wish to be limited only by the claims hereto appended.

I claim as my invention:

1. A tool for piercing a tube from the inside comprising an elongated member having a handle at the rear end, the handle being tapered toward the front so that the member is relatively thin at a given distance from the front end of the member, at the thin region the taper changing so that the member becomes progressively thicker toward the front end, near the front end the member is formed to have the general shape of a skull and is provided with a tooth in the region of the two upper front teeth on a skull, whereby the tooth may be caused to pierce the tube from the inside when the front end of the member is inserted in a tube whose inside diameter is not materially greater than the vertical diameter of the skull and the member is moved to cause the skull to nod.

2. A one-piece tool for piercing a tube from the inside comprising an elongated member having a tube piercing cutter at the front end and a tool manipulating element at the rear end, the elongated member having a thickened portion directly to the rear of the front end of a diametrical dimension not materially less than the inside diameter of the tube that is to be pierced from the inside and of lesser diametrical dimension for the remainder of its length so that the elongated member, when inserted in the tube, may be moved angularly with reference to the axis of the tube to thus cause radial movement of the cutter as its thickened portion is fulcrumed in the tube, whereby a hole may be cut in the tube from the inside of the tube upon suitable angular manipulation of the element at the rear end of the member.

3. For the manufacture of a heat distributing block for a heated Pitot tube wherein the block is provided with two axially disposed wells that are to be in communication at the bottom, a tool for piercing the material between the wells at the bottom of the well, said tool having a straight bottom portion for the greater portion of its length except near the end where the material is removed for a short distance toward the axis 60 of the tool but the very end portion being left in place, said end portion that is left in place being shaped into a piercing element, the portion of the tool above the piercing element being curved backwardly and being bulb-shaped so that its 65 dimensions and shape nearly fill one of the wells in the block, the region back of the bulb portion being made thinner so that the tool can be moved angularly in the plane including the axes of the wells and when so moved so as to make a greater angle with the axes of the well will at the bulb

region engage the walls of the well as a sliding pivot and cause the material piercing end to pierce the material between the wells.

4. A tube piercing tool comprising, a generally skull-shaped front end with a tooth at the region of the two upper front teeth of a skull, a handle tapered to have a thin end and a thick end, the

thick end being secured to the back of the skull, whereby the tooth will pierce the material when the tool is inserted in a tubular member having a diameter not materially greater than that determined by the arc of the skull taken on a vertical plane and is moved to cause the skull to nod.

ELDRED O. MORTON.
